UNITED STATES PATENT OFFICE.

HARRY TOWER DOWNS, OF NEW YORK, N. Y., ASSIGNOR OF ONE-HALF TO
LOREN N. DOWNS, OF SAME PLACE.

FIRE-ALARM SYSTEM.

SPECIFICATION forming part of Letters Patent No. 505,819, dated October 3, 1893.

Application filed October 1, 1892. Serial No. 447,560. (No model.)

To all whom it may concern.

Be it known that I, HARRY TOWER DOWNS, a citizen of the United States, residing at New York, in the county of New York and State of New York, have invented certain new and useful Improvements in Fire-Alarm Systems; and I do hereby declare the following to be a full, clear, and exact description of the invention, such as will enable others skilled in the art to which it appertains to make and use the same.

This invention relates to fire alarm systems for use in hotels or buildings or groups of buildings where the alarm is to be transmitted from one of a series of stations such as the stories or sections of a building to a common station at which it may be retransmitted to a series of points where warning is needed.

The object of the invention is to render the alarm transmission from the common station automatic in operation.

The several features of novelty will be hereinafter more fully described in this specification and definitely indicated in the appended claim.

In the accompanying drawings which illustrate the invention Figure 1 is a diagrammatic view of an alarm system embodying my invention. Fig. 2 illustrates the receiver used at the central office or common station, adapted to indicate to a clerk or employé in charge the location of the fire and to automatically send out the alarm. Fig. 3 illustrates the type of gong used in my system.

My system may be installed in a hotel, factory or other large building or may include a series of buildings or even a town or city. At a series of points throughout the installation easily accessible in case of discovery of fire, is placed a series of transmitter boxes A containing a break wheel by which a series of electrical impulses indicating the location of the box may be transmitted to the common station. As illustrated in Fig. 1 the system is adapted for use in a building where the transmitter boxes are distributed over the several stories and connected in multiple relation to a circuit passing through a magnet in a receiver B at the office. Each transmitter as will be understood from Fig. 1 comprises a break wheel C co-operating with a contact spring, the circuit being normally

open. The transmitter box is provided with a crank by which an actuating spring may be wound in the usual manner and the break wheels in the several boxes have different numbers of teeth or contacts. The operation of any transmitter sends through the receiver magnet a series of impulses corresponding to the number of the box. These impulses energize a magnet D of the receiver, see Fig. 2, and through a suitable pawl and ratchet mechanism rotate an indicator step by step upon which are indications, one of which may be seen through a slot E in the cover of the receiver. Upon the shaft of the indicating disk is mounted a metal disk F in which is set a section of insulating material upon which when the receiver is not in action bears a contact spring G adapted to operate an alarm circuit. The several gongs included in this circuit are so organized that the entire force of the battery can be concentrated on the releasing magnets one at a time so that a smaller battery power will suffice for a successful operation of all the gongs. A rheotomic bell is mounted on the receiver comprising magnet H and automatic vibrator placed in a return branch of the gong releasing circuit, the point of connection with the gong releasing circuit being beyond the break formed by the insulating segment in disk F. Thus the operator at central office will be notified by the bell and the indicator will show the point of origin. The interposition of the automatic bell magnet of the receiver in the gong controlling circuit insures a continuance of the alarm at the office until the receiver had been reset. This resetting may be accomplished by operating a push which releases a check pawl I of the ratchet wheel of the receiver and permits a spring not shown to restore the ratchet to its normal position when the insulating segment supporting the contact spring G opens the alarm circuit. The several alarm gongs are electro-mechanical, the gong circuit being at the instant of closure at the receiver complete through the releasing magnet of the first gong only. The armature of the releasing magnet holds a contact arm L against a stop J and when the armature is actuated the arm drops opening contact at J and closing it at K. Thus at the instant of closure of the alarm circuit

the releasing magnet of the first gong is operated and the contact arm drops opening the circuit through the releasing magnet and closing the circuit to the next gong releasing magnet through contact stop K. Suitable means as for example a push button should be provided for lifting arm L and restoring the armature to its normal position.

The operation of the system is as follows:

- 10 The transmitter upon being actuated closes the circuit from battery M through the magnet D of the receiver at the office, the successive impulses of the transmitter break wheel rotating the indicator shaft against the tension of its spring.
- 15 The first closure of the circuit brings the spring G into metallic contact with the disk F thus closing the circuit of the battery N through the vibrator magnet H of the receiver over the path 1, 2, 3, disk F, spring G, wire 4, binding post, magnet H and its vibrator, wires 5 and 6 back to battery N. Another branch is completed from wire 4 to binding post, wire 7, switch O, wire 8, contact arm L (see Fig. 3) contact J, releasing magnet of first gong and back to battery by wire 9. The gong releasing magnet being actuated the circuit is opened and the arm L completes the circuit through the releasing magnet of the next gong by conductors 10, 11, this action being continued through any number of gongs it may be found necessary to employ. Mean-
- 20 time the action of the transmitter has closed
- 25
- 30

and broken the circuit a number of times depending on its location and the indicator in the receiver exposes through the slot the approximate location of the fire, so that measures may be taken at the office to extinguish it. There may be a series of alarm circuits controlled by the battery N and proceeding to different parts of the building and these may be coupled in series or multiple are relation to the battery. Switches O, O' are provided at the office by which an alarm may be sent from the office independently of the receiver.

45

Having thus described my invention, what I claim as new, and desire to secure by Letters Patent, is—

In a fire alarm system the combination of a series of transmitters at outlying stations, a receiver at a common or central station, an alarm circuit controlled by said receiver, a series of electro-mechanical gongs controlled by said alarm circuit, each gong normally disconnecting the next gong from the circuit but provided with a circuit closing contact to complete the connection when its armature is actuated.

In testimony whereof I affix my signature in presence of two witnesses.

HARRY TOWER DOWNS.
